ABSTRACT OF THE DISCLOSURE

A device for electrochemical grinding by removing material from the surface of a conducting workpiece, comprising a conformator tool including two separate members, a first member for a quick attack of a rough shaped workpiece, comprising a support, one front-end of which is shaped as the compliment of the sectional contour to be obtained along the outer periphery of the workpiece, which operates during a first step of the operation; a high electrolyte flow output supply; a high-density current electricity source; and the second member is an electrolytic grinder operating at the rear part of the support, for grinding the workpiece to the desired final shape, the rear part of the support constituting a damming bulk for the electrolyte.

The present invention relates in general to electrochemical grinding methods and apparatus, and has specific reference to improvements brought to these methods and apparatus with a view to increase considerably the rate of shaping of the workpiece to be treated while reducing appreciably the cost of the device for a given degree of precision of the operation.

Electrolytic grinding devices are already known wherein a driving diamond grinding wheel receiving a negative charge and consisting of sintered copper is pressed against the workpiece connected to the positive terminal of a generator.

However, during this process a problem must be solved; this problem lies in the simultaneous presence of two contributing effects. In fact, the greater the contact surface area and the shorter the distance between the grinding wheel and the workpiece, the faster the electrolytic machining operation, since these conditions promote the passage of current and therefore the erosion of the anode-forming workpiece.

Thus, in said electrochemical process during the initial contact between a grinding wheel and a circular workpiece, only very moderate areas tangent to the two members involved are actually operative; thus, the electric exchange or transfer is rather limited, and therefore the attack is relatively moderate.

In contrast thereto, when the tool has penetrated more deeply into the workpiece, so that the latter's surface has assumed a shape complimentary to the wheel shape, the greater surface areas in mutual contact promote a stronger electrical exchange, thus producing a faster grinding action.

However, another factor becomes effective concurrently with the above-defined one:

2

The rapidity of the attack is also proportional to the electrolyte output at the interface formed between the grinding wheel and the workpiece; now, this electrolyte output will always be greater during the initial period of the machining operation, when nothing prevents its flow between the workpiece and the grinding wheel.

On the contrary, during the operation, i.e. when the tool has worked its way into the workpiece material, the electrolyte undergoes a loss of pressure due to the restricted flow passage so that its output is impaired.

Moreover, considering the fact that in the case of electrochemical grinding it is necessary, unlike what is observed in the case of a simple electrochemical attack, to maintain an actual physical contact between the abrasive particles of the grinding wheel and the workpiece to be shaped, under these conditions only a very limited electrolyte output can flow between the two members.

It is the primary object of the present invention to avoid the above-disclosed inconveniences by permitting the delivery of a large electrolyte flow capable of promoting a fast attack of the workpiece to be shaped while producing between the wheel and the workpiece a contact close enough to ensure an efficient abrasive action.

Basically, the present invention is characterized by the combination, in a same operation, of successive attacks of the workpiece to be shaped by an electrolytic tool operating under a relatively large electrolyte output and with a high current density, so that said tool can operate very rapidly, with an electrolytic grinding action for grinding the previously obtained surface to its final dimensions.

In the drawings:

FIG. 1 is a diagrammatic side-elevational view of a first embodiment of this invention, and

FIG. 2 is a similar view showing a modified embodiment.

Referring more in detail to the drawings, FIG. 1 illustrates a workpiece 1 connected to the positive terminal of a generator during the shaping of the workpiece by the electrolytic shaping tool 2 and the electrolytic grinding wheel 3 provided or not with abrasive elements and both connected to the negative terminal of said generator (not shown). The electrolytic shaping tool 2 consists essentially of a massive member of which the lower end portion 8 has a contour complimentary to the sectional shape to be obtained or reproduced along the outer periphery of workpiece 1. This tool 2 is carried by arms 9 connected to a link 7 or to any other suitable and known means permitting of presetting the tool 2 and more particularly adjusting the distance from this tool 2 to the workpiece 1.

The shaping tool 2 is connected via a conductor 4 to the negative terminal of the generator. It is supplied with electrolyte by means of conduits or hoses 5 and 6 controlled separately by valves 10, 10' and leading to the shaping tool proper and also to the grinding wheel 3; it will be seen that an inner volume is formed between the grinding wheel 3 and the rear portion of the tool 2, to promote the accumulation of electrolyte carried along by the wheel rotation and caused to engage the workpiece 1 at point B, where the grinding wheel is operative.

During the grinding operation the workpiece 1 and grinding wheel 3 are rotatably driven about their axes O and O' respectively in opposite directions, as shown by the arrows, and the tool 2 is moved towards the work-

piece by acting upon the link 7. The current generator has its positive terminal connected to the workpiece 1 and its negative terminal connected to both tool 2 and wheel 3.

Thus, the electrolyte is delivered *via* the hoses 5 and 6 and when the distance between the tool 2 and workpiece 1 is reduced sufficiently (but without producing an actual contact) the metal is attacked at A according to the shape of the surface 8 of tool 2.

Then, through its rotation, the previously machined surface of workpiece 1 is moved to point B at the level of grinding wheel 3 of which the surface has exactly the dimensions and shape of the desired workpiece 1 but in negative form.

The work performed at said point B consists in effecting an accurate grinding operation under a low current density.

As the greater part of the metal to be removed has already been eliminated (at point A), the wheel 3 removes at B only a few hundredths of a millimeter of this metal. Therefore, the mechanical stress applied to this wheel 3 is relatively moderate and the wheel material may consist of a light alloy or other light-weight, moderate-strength and relatively cheap material such as graphite, in contrast with conventional machines requiring the use of stress-resisting and considerably more expensive materials, such as sintered copper coated with diamond particles. The graphite grinding wheel, which is free of any abrasive substance and does not actually engage the workpiece, operating in this case only by electrolytic action.

The wheel 3 and tool 2 operate simultaneously until the entire outer periphery of the workpiece 1 has been treated by both means. However, when the rough-shaping tool 2 has completed its peripheral work, it is backed and disconnected automatically, and the electrolyte flow issuing from conduit 5 is cut off by closing the valve 10 to prevent a second pass which, in the long run, would remove excessive material from the workpiece 1.

This operation may be programmed or controlled through any known and suitable means such as a device for detecting the workpiece dimension, for example an electric photocell.

Similarly, these operations are performed immediately after the grinding wheel 3 has completed in turn its peripheral run on workpiece 1.

The modified form of embodiment illustrated in FIG. 2 departs from the preceding one in that the electrolytic tool 22 is mounted independently of the grinding wheel 23.

In this structure the homologues of the component elements already described with reference to FIG. 1 are designated and arranged as follows:

The workpiece 21 receiving a positive charge is attacked by the tool 22 and subsequently by the electrolytic wheel 23, both tool and wheel being charged negatively and supplied separately and adjustably with electrolyte at 25 and 26, respectively. The element 29 retained by spring 30 permits moderation of the electrolyte flow from hose or conduit 26. The tool 22 is adapted to be positioned by means of a known device 27 consisting for example of a handwheel controlling the longitudinal and transverse movements of said tool.

The operation of this structure is substantially identical with that of the structure shown in FIG. 1, and comprises the following steps:

quickly attacking the blank at A with electrolyte, grinding the workpiece 21 to the final dimensions at B by means of the electrolytic grinding wheel 23, automatically retracting the tool 22 and wheel 23, and also the workpiece 21 upon completion of the peripheral treatment thereof, concomitantly with the cutting off of the current and electrolyte supplies.

The essential differences between the two forms of embodiment may be described as follows:

The shape of the shaping end 28 of tool 22, which operates only through a profile, whereas the homologue end 8 of tool 2 operates throughout its oblique surface, thus requiring a more sophisticated and therefore more expensive tool in the case of FIG. 1.

The direction of rotation in the embodiment of FIG. 2 is such that the rotational speeds of the grinding wheel and of the workpiece add themselves at point B, thus improving the machining performances and efficiency.

The adjustment of the working position of the electrolytic tool 22 is completely independent of that of grinding wheel 23, an advantage not obtained with the arrangement of FIG. 1.

It would not constitute a departure from the basic principle of the present invention to modify various details of the device, for example with a view to machine workpieces having different shapes, as will readily occur to those conversant with the art.

What is claimed as new is:

1. A device for electrochemically grinding workpieces by removing material from the surface of conducting workpieces, comprising: tool means for shaping a movable workpiece, a source of electrical current having one pole connected to said tool means and a second pole for connection to a workpiece; means for supplying an electrolyte fluid to said tool means; said tool means comprising a first member for rapidly electrolytically attacking a rough-shaped rotating workpiece said first member comprising a support forming an electrolytic tool having a stationary front end shaped as a complimentary negative of the sectional contour to be obtained on a workpiece, and including means for inputting a high flow of electrolyte fluid and a terminal for a high-density current supply; and a second member comprising an electrolytic grinding wheel located separate from, but at the rear part of, said support, for grinding a rough-shaped workpiece after passage of said workpiece near said first member support; and the rear part of said support additionally comprising a damming bulk for retaining electrolyte fluid.

2. The device of claim 1, wherein said first member is secured to support means which is adjustable for locating said first member.

3. The device of claim 2, including means for rotating said electrolytic grinding wheel and a workpiece in the same direction of rotation.

4. The device of claim 1, including means for rotating said electrolytic grinding wheel and a workpiece in opposite directions of rotation.

5. A device for electrochemically forming workpieces, comprising: means for removing material from the surface of an electrically conductive workpiece, comprising a first tool having

a stationary working surface shaped as the compliment of the sectional contour desired to be obtained on a workpiece, with means for supplying electrolyte fluid through said first tool to said working surface, and means for supplying a high density current to the working surface of said first tool;

and a second tool comprising an electrolytic rotating grinding wheel and means for supplying electrolyte fluid to a nip space between the surface of said wheel and the path of the surface of a rotating conductive workpiece, and means for supplying a current to the surface of said grinding wheel;

said second tool being located downstream from said first tool along the path of the surface of said rotating conductive workpiece;

adjustable support means upon which said first tool is supported for adjusting the position of the working face of said first tool with respect to the path of the surface of said rotating conductive workpiece; a source of electric current having one pole connected to said tools, and another pole connectable to a conductive workpiece;

means for controlling the amount of electrolyte fluid supplied to said nip space in proportion to the size of said nip space; and
means for retaining said electrolyte fluid emerging from the path of the surface of said rotating conductive workpiece.
